MUD DISPERSION APPARATUS

Vernon B. Zacher, Ventura, Calif.

Application July 6, 1942, Serial No. 449,901

12 Claims.

(Cl. 259—6)

My invention relates to an apparatus for accomplishing the dispersion of flocs formed in drilling muds during use.

This application is a continuation in part of my pending application Serial No. 337,411, filed May 27, 1940.

In the operation of modern day drilling of oil wells, the practice is to force down through the drill pipe a mud mixture which serves to lubricate the bit, assist in the cutting, and also to carry the cuttings out of the well. There are other advantages inherent in the use of drilling mud, such as supporting the walls of the hole, sealing off porous formations, cooling the bit, etc. Because of the many functions it must perform, it is essential to keep the mud in the best viscous condition for the particular job at hand.

In the past, by one means or another to be referred to later, the drilling fluid has been treated in an effort to give it the viscosity yield strength or gel strength most conducive to its being pumped down the drill pipe. The body of mud moving upwardly in this mile or two mile drill pipe passage is sometimes called the slug flow.

After the drilling fluid has passed down the drill pipe and has lubricated the bit, picked up the cuttings and has moved slowly, as a slug, up the mile or two mile passage around the outside of the drill pipe, it has changed considerably in its physical make-up. It has much greater viscosity or stiffness than when it was originally introduced into the drill pipe on its down trip; and as it emerges from the top of the well it is usually then in no condition to be recirculated without retreatment.

This retreatment of the mud must take care of several different conditions brought about during its trip down the well. For example, my apparatus is to be distinguished from mixing devices for drilling mud, in all of which the problem is simply to get the various components to the mixture at the start of the drilling operation, although it may be employed during the drilling period. Such mixing machines are typified by the Sonstagen Patent No. 1,363,368. Also, my invention is to be distinguished from devices which relate to the problem of freeing the mud slug from entrapped gas by means of paddles operating at 200 R. P. M. in a vacuum chamber as taught by the Henst Patent No. 2,142,270. Each of the above devices would be used on a drilling job when the particular problem they relate to is encountered. However, neither takes the place of or would do what my device and method does in regard to the particular and different problem it deals with,

namely, chopping up the flocs which have formed in the mud.

Upon emergency from the top of the well the mud is overflowed into a ditch by way of an overflow pipe. It is not uncommon for the viscosity of this slug flow to be so great as to plug the overflow pipe and cause the mud to spill over the well head into the cellar. The high viscosity of this slug flow also makes it difficult to move it in the ditch on its way to the various treating devices, such as mentioned above, and eventually back into the drill pipe.

A condition of high viscosity (yield strength) of the drilling mud can interfere as much as any other factor with satisfactory drilling progress. The flocculation which often produces this high viscosity, gives the fluid a fluffiness and lightens it so that pump troubles follow. In addition to this the high viscosity cuts down the rapid flow of the fluid through the bit holes in the bottom of the well and robs the fluid of its "hydraulicking" jet value in making the hole. Today much reliance is placed on the supplementary cutting effect of this fast flowing mud being ejected from the bit holes.

In the past, in order to reduce the viscosity or gel strength of the mud, resort has been had to chemicals to disperse a flocculated condition. Still another method has been to employ large pumps to lift the mud into riffle towers, from which it tumbles over a series of steps, the tendency being to reduce its viscosity or gel strength. Each of the above schemes is very costly, requiring expensive pumping equipment or chemicals, and gives only an approximate result, as contrasted with the positive results of employing my method and apparatus.

I have found that chopping blades, located near the bottom of the ditch adjacent the outlet from the well, if operated at a very high speed, will transform the thick slug flow into an easy flowing drilling fluid. Exactly why this should be the case I have not been able to ascertain and therefore I advance the following explanations with the understanding that subsequent experiment may show the result achieved to be due to causes not now appreciated, but which are inherent in my method and apparatus.

It seems that as the mud moves through the well casing, moving at the rate of about one mile an hour during its passage up the mile or two miles of well hole, the particles tend to flocculate, that is, they tend to attract each other and grow in size due to adhesion or cohesion. With the growth in particle size of these elements, the vis-

cosity or stiffness of the mud rises perceptibly. When the slug flow emerges from the top of the well hole the first problem is to disperse this flocculated mud and break it down into as small particles as possible so it will be in condition for subsequent treatment and use.

My invention might be likened to placing these flocs on a chopping block and then chopping them with a knife moving at high velocity. The slowly moving stiff mud provides the chopping block and the blades rotating at high velocity do the chopping or shearing. They also do more, for it appears that as each layer of flocs is chopped or sheared from the face of the advancing mud stream, they are thrown into a vortex, where their affinity is further broken. They appear to come under the influence of the chopper several times before they move out of this vortex. The mud beyond the vortex is very much reduced in viscosity, the flocs are broken up, and it is ready to be treated for gas removal as suggested by Henst No. 2,142,270, if that is a problem on the particular well being drilled.

It is, therefore, one of the objects of my invention to provide an apparatus capable of dispersing these flocs, so that the mud can move on down the ditch and receive any further treatment for other conditions to be overcome before it starts down the well tubing on another trip.

Another object of my invention is to provide novel apparatus capable of dispersing these flocs, without impeding the continuous movement of mud in the ditch, and where necessary, giving a sufficient propelling force to the treated mud to keep it moving and to prevent it from overflowing the casing head or the ditch. The mechanism exerts extremely little action to force mud down ditch, and, in effect, really does little more than allow flow to be unimpeded. The free flowing tendency down ditch is, of course, mostly caused by the reduced viscosity as would be expected.

Another object of my invention is to provide an apparatus by which one or more very high speed choppers establish a shearing or chopping face in the mud stream from which the mud is chopped off in thin layers by the rapidly rotating knives or choppers and the chopped off portion is thrown into what might be described as a vortex.

In a sense, it is making little ones out of big ones by means of the high speed operation which chops or shears, and then throws the dispersed flocs into the vortex from which they emerge into the mud stream.

Other objects of my invention will appear from the description and drawings as I have not attempted above to state them all. Nor is this description intended as more than full compliance with R. S. Sec. 4888, requiring the explanation of one mode of applying the invention, which compliance does not limit the invention to the illustrative embodiment, except as required by the appended claims.

In the drawings are shown several forms of apparatus for practicing my method. It is obvious that other changes could be made in the apparatus and still practice the method, and it is not my intention to limit the apparatus except as required by the appended claims.

In the drawings, in which similar reference numerals refer to like parts:

Fig. 1 is an isometric view of a portion of a well near the surface showing the apparatus of my invention mounted in the mud ditch;

Fig. 2 is a view in side elevation, partially in cross-section, showing details of construction;

Fig. 3 is a view in end elevation taken on the line III—III, of Fig. 2;

Fig. 4 is a view in side elevation, partly in cross-section, showing a modified form of apparatus;

Fig. 5 is a similar view of another modification;

Fig. 6 is a view in side elevation, partly in cross-section, showing another modification.

In the drawings, numeral 10 indicates the well casing which may or may not extend to the bottom of the well, depending upon the formations encountered and the depth of the well. In any event, it is sufficiently tight to provide a conduit for returning to the surface the drill fluid or mud introduced in the drilling operation. The drill pipe 11 extends to the bottom of the well and at its lower end is secured the bit or drilling tool (not shown) and down through its center is circulated the drilling fluid or mud for purposes already pointed out. As this drilling fluid emerges from the top of the well casing 10 it overflows into pipe 12 and thence to the mud ditch 13 through a suitable pipe 14.

I prefer to fabricate my apparatus as a unitary structure, adapting it for ready placing in and removal from ditch 13. The apparatus includes the housing 16 and suitable bulkheads 15 with hinged wings 15a. The latter serve to guide the mud through housing 16 where it is treated. After the mud is treated in housing 16 it is conducted through suitable ditches to the pit from which it is pumped down the drill pipe. Before the mud reaches the pit it may be passed through screens which remove the cuttings, shale and any other hard particles which it carried to the surface, and it may pass through a device like Henst No. 2,142,270 for gas removal treatment.

The chopping or shearing apparatus employed in my method of reducing the viscosity or gel strength of the thickened mud, comprises one or more choppers 20, 21 arranged to rotate in casing 16 near the bottom of ditch 13, where they may be operated at very high speed. They may have an inclined face to impart a slight impelling effect. Preferably, they are mounted on a shaft or shafts set at an angle less than 90° with respect to ditch 13 so that the net effect will be to impart movement, or at least not to impede movement, of the mud down the ditch.

In Fig. 2, chopper shaft 22 is mounted at an angle of 72° in relation to the floor of the ditch.

In Figs. 4, 6 it is mounted at an angle of 60°. The preferable range seems to be 75° to 60°. In devices like Fig. 5, the shaft 22 may be substantially parallel with the floor of ditch 13.

I have obtained very fine results from using a pair of choppers 20 and 21 mounted on shaft 22 which is carried in suitable anti-friction bearings arranged in housing 25. A motor 26 or other suitable driving means may be employed for rotating shaft 22.

The chopper 20 is rigidly secured to shaft 22 with its impeller faces set at an angle of 20-22° from a plane perpendicular to the axis of the shaft. In one device tested, the diameter of this chopper was about 5½ to 6". The impeller faces were set so that upon rotation of shaft 22 the mud was deflected downwardly in a general direction toward the right hand end of housing 16. Chopper 21 was also rigidly mounted on shaft 22 and had its impeller faces set at an angle of 15-17° from a plane perpendicular to the axis of the shaft. It was of slightly smaller size than chopper 20, being from 5 to 5½" in diameter.

The impeller faces were set in a direction opposite to the corresponding faces of chopper 20 so that upon rotation of shaft 22 they impelled the mud in an upward direction or counter to the direction imparted by chopper 20. Being of a smaller size and with the blades set at a lesser angle than chopper 20, the latter was the predominant one of the pair and assisted movement of the mud down the ditch. In relation to direction of rotation the set of the impelling faces on the choppers is such that they act like a knife or chopper and lift or throw the severed flocs away from the point of cutting. For example, in Fig. 3 the shaft would rotate counter-clockwise looking down the shaft from the motor end.

It is preferable in a plural chopper apparatus, in order to interfere as little as possible with downstream movement of mud through casing 16, to have the larger or more effective chopper arranged in an upstream position in relation to the less effective chopper. It is to be understood that the effectiveness of a chopper may be varied by changing its diameter or by the angular set on the impelling face, etc., consequently, when I use the term "more effective impeller," I am not necessarily referring to one with a larger diameter.

The shaft housing 25 is welded or otherwise secured at 66 to housing 16. The latter is perforated at 27 to permit entry of shaft 22 with a slight clearance.

In the drawings is shown a hopper 23 fitted to housing 16 at 24, preferably directly above the vortex created by the impellers. By means of valve 30 controlled by rod 31 threaded in web 32 the hopper contents (usually chemicals) can be fed into housing 16 in the quantity desired. The choppers 20, 21 will cut the chemicals into the mud.

The whole unit may be securely mounted in ditch 13 with bulkheads 15 resting securely on the bottom, by means of collar 29 to which is attached horizontal angle member 34 adapted to rest on or be secured to the top of the trough sides. Upon loosening this collar 29 supporting arm 34 can be brought to rest on the top edges of ditch 13. A gate 35 is mounted to slide in a slot 36 in the downstream end of housing 16. A spring 37 holds it in any selected position. By use of gate 35 a good working level of mud in housing 16 can be assured.

The modification shown in Fig. 4 differs from Fig. 2 only in respect to the tilt to shaft 22 and arrangement of choppers 20 and 21. In Fig. 4 the mud movement is to the right and chopper 21 is arranged to be more effective than chopper 20, so that the net effect is for the chopped mud to emerge from the vortex with a slight directional movement downstream. Shaft 22 slopes to the right, preferably at an angle of 60° to 75° to the bottom of ditch 13.

The modification shown in Fig. 5 employs two choppers 20, 21 arranged on shaft 22 which may project from upper end wall 70 of ditch 13 or be rotated by other suitably mounted drive. Mud movement is to the right. Chopper 20 is preferably slightly more effective than chopper 21, although it need not be as the sheared off flocs entering and then emerging from the vortex will tend to travel downstream with the general mud movement.

The modification shown in Fig. 6 is substantially like the one in Fig. 2, except that choppers 20, 21 are made of equal effectiveness.

The devices just described are particularly ef- 75

fective in breaking up the flocs, presumably by a shaving, chopping, or shearing action combined with a throwing or impelling of the severed portions away from each other in a vortex, so that they do not re-unite to reform the larger floc, in which form it emerged with the slug flow from the well.

As stated earlier, the high velocity of the chopper blades moving adjacent the face of the slowly advancing mud appears to have the same effect as if the flocs were placed on a chopping block and then chopped with a keen knife at high velocity. The face of the advancing mud stream seems to hold the flocs, while the blades chop them off. The mud is chopped, then it is thrown into and out of the vortex. This action is to be distinguished from mixing or moving a fluid with a propeller. In my device and method there is no particular speed up in movement of the mud in ditch 13.

The purpose of my device is not to move the mud in ditch 13. If the choppers acted like a mixer or screw feed pump they would speed up mud movement along ditch 13 to at least twice its normal rate. This would be bad because it would scavenge the ditch above the choppers and prevent submerged operation for the choppers.

Because of the above, the matter of velocity or speed of rotation of the chopper or choppers is important and gives my new result. This velocity can be determined on the following basis. Select the normal and desired volume and rate of movement of mud in ditch 13. Select the speed most satisfactory for shaft 22 and divide it by two. Then calculate from these factors the size and pitch of an impeller face which would move the mud in ditch 13 at the desired normal rate with shaft 22 turning at half speed. With such an impeller face operated at normal speed instead of half speed, one is usually assured of obtaining sufficient velocity to avoid pumping on the one hand, or cavitation on the other, and to obtain the desired chopping action. This is given as an example and not with the idea that doubling the impeller speed is the critical speed. It is a speed which does appear to give good results.

The important thing is to have the speed of shaft 22 and the chopper or choppers of a size and angular set on their impelling faces such that these faces lose most of their pumping impelling function in favor of the chopping or shearing function of the choppers. The top limit on the speed range should be just below the point at which cavitation begins to manifest itself. I have found satisfactory results with a range in velocity of between 3600 to 5200 linear feet per minute in periphery of the upper chopper in treating average colloidal mud systems. However, these speeds are mentioned only as illustrative within the definition for calculating speeds as given above.

These have an important bearing on the ability of the chopper-impellers to create a vortex or vortices as they throw off the chopped flocs. For example, the thickness of layer chopped from the face of the advancing mud wall on each revolution is only a fraction of the thickness of layer that would be peeled off if the device were being used as a mixer or as a pump to move the mud in ditch 13.

I have found the devices shown in Figs. 2, 4, 5 and 6 to be particularly efficient. The chopper-impellers are set to produce impinging vortices of the severed particles. This apparently creates

a maximum zone of turbulence and impingement in housing 16 so that very little mud escapes the chopping treatment.

I have tried in Fig. 2 to illustrate what paths the highly viscous untreated mud takes and how the chopper-impellers act on it. The dotted lines 40 and 50 indicate roughly the innermost faces or boundaries of the untreated mud slug as it moves up into position, and the arrows 41 and 51 indicate its general direction of movement into the chopping zone. The high speed of rotation of choppers 20 and 21, coupled with the high viscosity of the untreated mud, results in a chopper causing the mud above chopper 20 and below chopper 21 to take the form substantially of the profile of the edge of the chopper-blades. It is something like a vortex or whirlwind. On each rotation the choppers cut or sever a thin layer of this highly viscous mud wall and throw or impel these severed particles in the general direction of the arrows 42 and 52 to form a vortex. These severed particles are not only thrown toward each other, but are also subject to a centrifugal action in the vortex which, judging from the results obtained, effects a thorough deflocculation of the mud. There is every indication that the flocs which enter the vortex are passed through the choppers several times before they are thrown out and move downstream.

Because the larger chopper-impeller 20 is set to act in the downstream direction, the net effect is for the deflocculated mud to be assisted in its movement in that direction.

While to illustrate my invention I have described apparatus having a single shaft 22, it is obvious that a shaft for each chopper might be employed as the means for rotating the choppers.

What I claim is:

1. An apparatus for mechanically dispersing a flocculated colloidal system in a mud slug moving slowly in a ditch, means including a shaft set at an angle to the axis of said ditch, means for supporting said shaft operatively in said ditch, means for rotating said shaft, a plurality of chopper-impeller means secured to said shaft in spaced apart relation along the axis of said shaft, a portion of said chopper-impeller means having their impeller surfaces arranged at angles to throw flocs chopped from said mud slug into the area between them.

2. In a mud floc dispersing apparatus adapted to operate submerged in a ditch full of a slow moving mud slug, the combination of a frame, a shaft set at an angle to the axis of said ditch, means for rotating said shaft at high speed, a chopper and impeller on said shaft and a second chopper and impeller on said shaft spaced apart from the other, the impelling surfaces on said choppers being disposed so as to throw the severed mud flocs toward each other.

3. A mud treating device comprising a frame for positioning over a mud ditch, a shaft rotatably supported by the frame, said shaft being downwardly inclined from the frame in the direction of mud flow in the ditch, means for imparting rotation to the shaft, and a pair of oppositely set mud cutting and impelling members secured spaced apart along the shaft adjacent the lower end thereof, the lowermost member being smaller than the other member.

4. A mud treating device comprising a frame for positioning with respect to a mud ditch, a shaft rotatably supported by the frame, said shaft

extending from the frame into the mud ditch at an angle less than a right angle to the axis of said ditch, means for imparting rotation to the shaft, and a pair of oppositely set mud cutting and impelling members secured spaced apart along the shaft adjacent the lower end thereof, the member farthest downstream being smaller than the other member.

5. A mud treating device comprising a frame for positioning with respect to a mud ditch, a shaft rotatably supported by the frame, said shaft being inclined in relation to the bottom of the ditch and extending from the frame into the mud ditch, means for imparting rotation to the shaft, and a pair of oppositely set mud cutting and impelling members secured spaced apart along the shaft adjacent the lower end thereof, the member farthest downstream being smaller than the other member.

6. A mud treating device comprising a frame for positioning with respect to a mud ditch, a shaft rotatably supported by the frame, said shaft being inclined in relation to the bottom of the ditch and extending from the frame into the mud ditch, means for imparting rotation to the shaft, and a pair of oppositely set mud cutting and impelling members secured spaced apart along the shaft adjacent the lower end thereof, whereby upon rotation of said shaft two zones of oppositely directed and severed mud will be produced.

7. A mud treating device comprising a ditch chamber having an inlet and outlet through which mud is free to flow, a drive shaft mounted in said chamber in a position inclined to the vertical in the direction from which the mud enters said chamber, means for rotating said shaft, a pair of severing and impelling means secured to said shaft, spaced apart vertically thereon, with their respective impelling surfaces oppositely set, and in which the uppermost of said severing means is made with a more effective impelling surface.

8. A mud treating device comprising a ditch chamber having an inlet and outlet through which mud is free to flow, a drive shaft mounted in said chamber in a position slightly inclined to the vertical in the direction from which the mud enters said chamber, means for rotating said shaft, a pair of severing means with impelling surfaces secured to said shaft, spaced apart vertically thereon, with their respective impelling surfaces oppositely set, and in which the uppermost of said severing means is made with a more effective impelling surface.

9. A mud treating device comprising a ditch chamber having an inlet and outlet through which mud is free to flow, a drive shaft mounted in said chamber in a position slightly inclined to the vertical, means for rotating said shaft, a pair of severing means with impelling surfaces secured to said shaft, spaced apart vertically thereon, with their respective impelling surfaces oppositely set, and in which the severing means farthest upstream is made with a more effective impelling surface.

10. A mud treating device comprising a ditch chamber having an inlet and outlet through which mud is free to flow by gravity, a drive shaft mounted in said chamber inclined in relation to the bottom of said ditch, means for rotating said shaft, a pair of severing means with impelling surfaces secured to said shaft, spaced apart axially thereon, with their respective impelling surfaces oppositely set.

11. Apparatus for rendering circulated viscous drilling mud sufficiently less viscous to permit of it being recirculated, comprising a conduit for the passage of said mud, upstream and downstream sets of radially disposed blades in said conduit and having comminuting edges, said upstream and downstream blades being twisted, and means inclined in relation to the axis of said conduit to rotate said blades at speeds sufficiently high to subject said mud passing thereby to very fine comminuting action and in such a manner as to cause said upstream twisted blades and said downstream twisted blades to oppose each other.

12. Apparatus for rendering circulated viscous drilling mud sufficiently less viscous to permit of

it being recirculated, comprising a conduit for the passage of said mud, upstream and downstream sets of radially disposed blades in said conduit and having comminuting edges, upstream and downstream blades being twisted, and means inclined in relation to the axis of said conduit to rotate said blades at speeds sufficiently high to subject said mud passing thereby to very fine comminuting action and in such a manner as to cause said upstream twisted blades and said downstream twisted blades to oppose each other, said upstream set of blades having a greater forwarding effect on said mud than said downstream set of blades.

VERNON B. ZACHER.
